ROTARY ENGINE

Carl B. Hansen, San Francisco, Calif.

Application October 11, 1943, Serial No. 505,886

3 Claims. (Cl. 123—11)

The present invention relates to improvements in rotary engines.

An object of my invention is to provide an improved rotary engine having a plurality of pistons circularly arranged for movement away from and toward one another in a predetermined manner to alternately provide their power and compression strokes for the purpose of actuating a number of cam members, which in turn impart rotary movement to a crank shaft and at the same time move the pistons circularly around the said shaft.

Another object of my invention is to provide an improved internal combustion engine of the rotary type wherein a number of pistons mounted for circular movement about a crank shaft are arranged to alternately move toward and away from one another on their compression and power strokes.

A still further object of my invention is to provide an internal combustion engine of the kind characterized having a novel and simplified construction wherein the pistons mounted in a circular chamber are arranged to alternately move toward and away from one another and at the same time move in a circular direction about the crank shaft.

The present invention provides a number of other objects and advantages which will be pointed out hereinafter, indicated in the appended claims, or will be obvious to one skilled in the art upon an understanding of the present disclosure. For the purpose of this application, I have elected to show herein certain forms and details of a rotary internal combustion engine representative of my invention; it is to be understood, however, that the embodiment of my invention herein shown and described is for the purpose of illustration only, and that therefore it is not to be regarded as exhaustive of the variations of the invention, nor is it to be given an interpretation such as might have the effect of limiting the claims short of the true and most comprehensive scope of the invention in the art.

In the accompanying drawings:

Fig. 1 is a vertical sectional view of a rotary engine embodying the preferred principles of my invention;

Fig. 2 is a sectional view taken on the line 2—2 of Fig. 1;

Fig. 3 is a sectional view taken on the line 3—3 of Fig. 1;

Fig. 4 is a sectional view taken on the line 4—4 of Fig. 2; and

Fig. 5 is a sectional view taken on the line 5—5 of Fig. 2.

Referring to the drawings, the numeral 1 designates a housing, made preferably in two sections, having water jackets 2 arranged therein. Journaled in the housing is an axially disposed crank shaft 3. Positioned in the housing and mounted for independent rotary movement on the crank shaft are piston carrying wheels or members 4 and 5 carrying pistons 6 and 7, respectively, at their peripheries or rims. The pistons of each wheel are arranged sixty degrees apart and each is provided for compression purposes at its opposite sides with sealing members 8. The pistons are adapted to move in a clockwise direction (Fig. 2) within an annular enclosed chamber 9 provided in the housing 1. The chamber is arranged concentrically with respect to the shaft and is enclosed at its inner side by the peripheries or rims of the wheels 4 and 5 and at its three other sides by the housing 1. Interposed 10 between the wheels 4 and 5 for compression purposes are sealing rings 10. Secured within suitable openings provided in the housing 1 are spark plugs 11 which are arranged sixty degrees apart. Suitable fuel intake and exhaust means 12 and 13 also positioned sixty degrees apart are provided in the housing. The intake and exhaust openings are arranged in pairs at predetermined 15 positions near the spark plugs 11.

Ducts 14 leading axially through the crank 20 shaft and extending radially as at 15 to connect with suitable channels 16 in the spokes of the wheels 4 and 5, and in the pistons 6 and 7, serve to supply a lubricant, delivered under pressure, for the operation of the crank shaft, the wheels 25 and the pistons. A suitable bushing 17 is interposed between the wheels 4 and 5 and the crank shaft 3.

Secured as at 18 to the housing 1 is a large stationary ring gear 19 having its teeth arranged 30 internally and in mesh with the teeth of three circular running gears 20. The running gears 20 are arranged one hundred twenty degrees apart, and each is axially and rotatably mounted at its outer side on a finger or projection 21 carried by a drive-disc 22 which is keyed as at 23 to the crank shaft 3. Each of the running gears 20 is provided at its inner side with an oval track or cam 24 within which projecting members 4' and 5', carried by the wheels 4 and 5, movably 35 extend. The projecting members 4' and 5' are arranged in pairs and are confined within the oval tracks 24, and as the pistons 6 and 7 are forced apart when the explosions occur, the said members are also moved apart. As the projecting members 4' and 5' are forced apart, they 40 will cause the running gears 20 to rotate in a

counter-clockwise direction and at the same time move clockwise within the ring gear 19, thereby carrying the fingers 21 of the drive-disc 23 in a clockwise direction and thus rotating the said disc and the crank shaft. During each power stroke the pistons 6 and 7, as well as the projections 4' and 5' of the wheels will be moved apart from their closest to their most widely separated relative positions and, simultaneously, the running gears 20 and their oval tracks 24 will be rotated one-quarter of one revolution. At each subsequent compression stroke the pistons and the projections 4' and 5' will be moved toward each other from their extremely separated to their closest relative positions, and at the same time the running gears 20 and their oval tracks 24 will be rotated in the same counter-clockwise direction a quarter of one revolution. The oval tracks or cams of the running gears through the engagement therewith by the projecting members 4' and 5' will direct and limit the relative movements of the pistons. The spark plugs 11 are arranged opposite the spaces in the annular chamber 9 where the combustion areas or chambers 9' are located, that is, at points where the pistons 6 and 7 reach their closest relative positions with respect to one another. The exhaust ports 13 are positioned adjacent the spaces where the combustion areas or chambers 9' occur, and each is covered by a piston when the pistons are in close proximity at the commencement of their power strokes. The intake ports 12 are located near the exhaust ports, and each is uncovered to admit fuel to a combustion chamber after a piston has moved across and beyond the adjacent exhaust port.

The firing in the six combustion chambers 9' takes place simultaneously, and immediately thereafter the pair of pistons 6 and 7 then located at opposite sides of each combustion chamber are forced apart. As these pistons are forced apart, the projections 4' and 5' carried by the wheels and operating in the oval tracks 24, are also moved in opposite directions, thereby causing the running gears 20 to rotate in a counter-clockwise direction. As the running gears 20 rotate in said direction, their teeth engaging with the teeth of the stationary ring gear 19, cause the said running gears to move bodily in a clockwise direction, and since the said running gears are connected by the fingers 21 to the drive-disc 22, the latter and also the crank shaft are rotated in the same direction. When the projecting members 4' and 5' have moved to their farthest-apart-positions, the running gears 20 and the latter's oval tracks 24 will have been rotated one-quarter of a revolution, and at the same time the pistons 6 and 7 of each pair will have been forced apart to the end or completion of their power strokes. At the beginning of the power stroke when the firing occurs, the exhaust openings 13 will be closed by the pistons 7 (see Fig. 2), but after the movement of the latter in a clockwise direction for a short distance, the said exhaust openings will be uncovered to allow the gases of combustion to escape. While the pistons 7 are in positions closing the exhaust ports 13, the intake ports 12 are sufficiently opened to admit the remainder of a fuel charge to the chamber 9, then, as the said pistons move in a clockwise direction (Fig. 2), the intake openings will be completely closed while at the same time the fuel charges in the chamber 9 will be in the process of being compressed preparatory to the succeeding explosion. During this movement of each piston

1, the then associated and adjacent piston 6 will be moved away from 7, but since the wheel 4 is then being carried by the running gears 24 in a clockwise direction (Fig. 3), the said piston 6 will 5 soon after the explosion, commence to move also in a clockwise direction, although at the same time it is becoming more widely separated from the piston 7. As the power stroke progresses, the pistons 6 move in a clockwise direction past the compression chambers 9' and the spark plugs 11, and gradually cover and close first the exhaust ports 13 and then partially the intake ports 12. After the exhaust ports have been closed, the 10 succeeding charges of fuel are admitted to the chambers 9. While the pistons 6 are moving to positions formerly assumed (at the commencement of the power stroke) by their then associated pistons 7, the pistons 7 which are following from behind on their power strokes, will have 15 moved on their compression strokes to the positions near the spark plugs formerly occupied by the pistons 6. The charges of fuel previously admitted to the chamber 9 will thereupon be compressed between the pairs of pistons 6 and 7 in the combustion chambers 9', ready for the next 20 firing.

It will therefore be noted that when the pistons 7 and 6 start on their power strokes, pistons 6 and 7 start on their compression strokes, and 30 when the power strokes are completed, pistons 6 and 7 are under full compression. As they start on their power strokes, pistons 7 and 6 are forced together again on their compression strokes, and 35 the projecting members 5' and 4' are forced together again, and as they are forced together they turn the oval tracks another quarter turn.

The six power strokes occur simultaneously, and since the running gears 20 make three revolutions to one revolution of the crank shaft, there 40 are seventy-two power strokes for each revolution of the crank shaft. Suitable means of the usual kind for providing the timely injection of fuel to the chamber 9 and for providing a spark for igniting the compressed charges of fuel are 45 embodiments of the engine, but for the sake of clearness and brevity they have been purposely omitted from the drawings. While I have shown and described a rotary engine having twelve pistons, it is to be understood that the principles of my invention may just as well embody types having eight, ten, sixteen, or any other suitable number of pistons and associated elements.

What I claim is:

1. In a rotary engine, a housing having a circular chamber, a shaft journaled in the housing and arranged concentrically with respect to the circular chamber, a pair of piston carrying members mounted for independent rotary motion on the shaft, a plurality of spaced pistons carried by 55 each piston carrying member and arranged for circular movement in the chamber, a stationary ring gear, a drive-disc secured to the shaft having spaced projections thereon, a plurality of spaced running gears meshed with the ring gear and rotatably mounted on the projections of the drive-disc, the said running gears being spaced at equal distances from one another and arranged to rotate and to move circularly around the shaft and rotate the drive-disc and said shaft, projecting members on each piston carrying member, cam members carried by each running gear with which the projecting members of the piston carrying members engage, the cam members being so constructed and arranged as to control the movement of the pistons of the respec-

tive piston carrying members after each explosion, whereby they move toward and away from one another to provide successive compression and power strokes, and fuel intake and exhaust means arranged in the housing for admitting fuel to the chamber and for exhausting the gases of combustion therefrom.

2. In a rotary engine, a housing having fuel intake and exhaust means and a circular chamber, a shaft journaled in the housing and arranged concentrically with respect to the chamber, a pair of piston carrying wheels mounted for independent rotary movement on the shaft, a set of spaced pistons carried by each wheel and arranged for circular movement in the chamber, a plurality of rotatable running gears arranged to rotate and to travel in a circular path concentric to the circular chamber, each carrying a cam of predetermined shape, projecting members carried by the wheels and positioned in engagement with the cams, the said projecting members and the cams being so constructed and arranged that when explosions in the chamber occur, the pistons will be guided in a definite manner away from and toward one another on their power and compression strokes and at the same time the running gears will be rotated and moved along their

10 circular path, and means connecting the running gears and the shaft, whereby when the running gears are moved circularly the shaft will be rotated.

5. In a rotary engine, a housing having an annular chamber wherein charges of fuel are exploded, a shaft journaled in the housing and arranged concentrically with respect to the chamber, a plurality of piston carrying wheels mounted for independent rotary movement on the shaft, a set of spaced and circularly arranged pistons carried by each wheel and mounted for circular movement in the chamber, a plurality of spaced cam members arranged for rotary and circular movement about the shaft, cam engaging members carried by the wheels, the cam engaging members and the cams being so constructed and arranged that when explosions occur in the chamber the set of pistons will be guided in a definite manner away from and toward one another on their power and compression strokes and at the same time the cam members will be simultaneously rotated and moved circularly, and means connecting the cam members and the shaft, whereby when the cam members are moved circularly the shaft will be rotated.

CARL B. HANSEN.
